CONTAINER

Bradford W. Brown, Northbrook, Ill., assignor
to Container Corporation of America, Chi-
cago, Ill., a corporation of Delaware

Application March 23, 1936, Serial No. 70,247

3 Claims. (Cl. 229—45)

The present invention relates to containers particularly adapted for the packing of ice cream and other edible materials which are intended to be made up in individual packages to be eaten 5 directly from the container.

One object of the invention is to provide a relatively liquid-tight container capable of being manufactured in complete form at the box plant so that the container may be shipped flat to the 10 user and set up by him without requiring any special machinery and without the use of fastening devices other than parts formed on the container itself.

A further object of the invention is to provide 15 a simple and effective locking means for retaining the cover on the container, such locking means being disposed adjacent the corners of the cover and body portion whereby the cover will be securely retained against accidental displacement.

20 A further object of the invention is to locate the locking parts so that they will be disposed substantially outside of the compartment in which the food is contained whereby the food compartment proper will be substantially smooth and free from irregularities thus minimizing like- 25 lihood of contamination by dust or other foreign matter.

25 A further object is to provide a container of the type described which will be extremely simple in form and easy to set up and use, and which will be effective for the purpose intended.

To these and other ends the invention resides in certain improvements and combinations of 30 parts, all as will be hereinafter more fully described, the novel features being pointed out in the claims at the end of the specification.

In the drawing:

Fig. 1 is a perspective view of a form of container made in accordance with a preferred embodiment of the invention;

Fig. 2 is a fragmentary detail view, partly in section, taken along the line 2—2 of Fig. 1;

Fig. 3 is a fragmentary perspective view of 45 one corner of the container showing the interlocking parts between the cover and the side wall;

Fig. 4 is a view of the blank of the body portion of the container; and

50 Fig. 5 is a view of the closure blank.

Similar reference numerals throughout the several views indicate the same parts.

The container of the present invention, as herein disclosed, comprises a tapered body portion or container proper and a cover portion for

the container each of which has cooperating interlocking parts formed thereon at the corners of the container so as to secure the cover against accidental displacement.

Referring more particularly to the drawing, 5 the body portion 1 of the container comprises a bottom 2, and side walls 3, 4, 5, and 6, all of which are preferably formed with outwardly tapered edges. See particularly Fig. 4. The walls 3 and 4 are provided respectively at their ends 10 with flaps 3a, 3b, 4a, 4b. These flaps are formed with conventional interlocking parts which engage with each other to retain the body portion 1 in set-up condition as illustrated in Fig. 1. The walls 5 and 6 are, in the present instance, first 15 folded inwardly so that they will lie inside of the assembled interlocking flaps 3a, 4a and 3b, 4b. Due to the construction just described it is apparent that the body portion of the container may be set up and retained in condition to effectively hold the desired material. Other conventional means may, if desired, be employed to retain the walls in container-forming position.

20 The cover for the container preferably comprises a closure panel 7 having extension flaps 8, 8 and 9, 9 thereon, all defined from the closure panel by the score lines indicated. By folding these extension flaps upwardly it is to be observed that a recessed closure is formed that will fit within the top of the body portion with the upper 25 edges of the extension flaps lying substantially flush with the upper edges of the side walls. The extension flaps are preferably flared outwardly so that when they are bent upwardly, the sides of the cover will substantially conform to the 30 taper of the side walls.

35 Means are provided adjacent the corners of the body member and cover for locking the cover to the body member. For this purpose recesses 10, 10 are formed in the edges of the side walls 40 5 and 6, and tabs 11, 11 are formed on the ends of extension flaps 8, 8, the position of the tabs 11, 11 being such as to cause them to engage within the recesses 10, 10 when the cover is properly 45 positioned on the body member. The tabs 11, 11 and recesses 10, 10, are preferably formed of similar shape so that the tabs will substantially fit within the respective recesses. The upper 50 edges of the tabs as well as the upper part of the recesses are formed so that the upper portions thereof immediately adjacent the corner of the container extend at approximately a right angular relation to the corner of the container. The upper part of the recesses will, accordingly, 55

provide an abutment serving to more or less positively retain the tabs 11, 11.

The tabs 11, 11 are preferably of such length that a substantial portion of the ends will lie against the inner surfaces of the interengaged flaps 3a, 3b and 4a, 4b and be deflected thereby to a position substantially at right angles to the extension flaps 8, 8, so that the edges of the tabs will abut the edges of the recesses. In other words, the ends of the tabs will lie substantially in the plane of the respective walls 5 and 6. Due to the presence of extension flaps 9, 9 resting against the walls 5 and 6 these flaps will serve to retain tabs 11, 11 from any possible inward movement; and, due to the presence of the interengaged flaps 3a, 3b and 4a, 4b, the tabs 11 will be prevented from any possible outward movement. Thus the tabs will be effectively retained within the recesses.

20 Small openings 12, 12 may, if desired, be formed in the flap extensions 9, 9 for the reception of the extremities of a spoon or similar utensil such as illustrated in my copending application, Serial No. 36,759, filed August 19, 1935.

25 In the use of the container of the present invention the body portion and cover will be shipped flat to the packer who desires to utilize the containers in the packaging of his products. It is only necessary for the packer to set up the 30 container by bringing the walls 5 and 6 to upright position and then interlocking the flaps 3a, 4a, 3b, and 4b. The body portion of the container is now ready to receive the edible material or other product which is to be packed therein. The 35 extension flaps on the cover will then be moved to upright position and the cover pushed down into the body portion until the locking tabs 11, 11 engage within the respective recesses 10, 10.

From the foregoing description it is apparent 40 that a convenient and effective form of container for edible materials is provided which can be packed flat for shipment to the user and by him readily set up and assembled without requiring special equipment. Due to the position of the 45 locking elements and their shape the cover is securely retained upon the body portion and the likelihood of its becoming accidentally displaced is minimized. At the same time the cover of the container may be readily removed by grasping and lifting one of the flap extensions of the 50 cover whereupon the locking tabs will become displaced from the recesses 10, 10 permitting the container to be readily opened for access to the contents.

55 While the present description sets forth a preferred embodiment of the invention, numerous changes may be made in the construction without departing from the spirit of the invention, and it is therefore desired that the present embodiment be considered in all respects as illustrative and not restrictive, reference being had to the appended claims rather than to the foregoing de-

scription to indicate the scope of the invention.

I claim:

1. A container comprising a bottom and four side walls, two oppositely disposed walls being of at least double thickness and comprising inner 5 and outer panels, a recessed cover portion for the container comprising a closure panel having upwardly foldable extension flaps thereon adapted to lie flat against the side walls of the container when assembled therewith, the inner panel 10 of the double thickness side walls having inwardly directed recesses formed at each upper edge thereof adjacent the corners of the container, and tabs on each end of two oppositely disposed extension flaps on the cover adapted to be received snugly within said recesses and lie against the outer panel of said double thickness side wall in substantially the plane of said inner panel to retain the cover in place.

2. A container comprising a bottom and four 20 side walls, interlocking flaps on the ends of two oppositely disposed side walls, said interlocking flaps being adapted to lie outside of and retain the other two oppositely disposed side walls in upright position whereby two oppositely disposed 25 side walls of at least double thickness are provided comprising inner and outer panels, a recessed cover portion for the container comprising a closure panel having upwardly folded extension flaps thereon adapted to lie flat against the side walls of 30 the container when assembled therewith, the inner panel of the double thickness side walls having inwardly directed recesses formed on each edge thereof adjacent the corners of the container, and tabs on each end of two oppositely disposed 35 extension flaps on the cover adapted to be received within said recesses to retain the cover in place, said tabs being of such length as to bear against the outer panel of the double thickness side walls and be deflected thereby so that a portion 40 of the tabs will lie flat against the outer side wall panel and substantially in the plane of the inner side wall panel whereby the edge of the material comprising the tab will bear against the edges of the inner panel at the recesses 45 therein.

3. A container having a bottom wall, four side walls, two oppositely disposed side walls being of double thickness, a closure panel having upwardly extending flaps along at least two opposed 50 sides, the inner wall panels of the double thickness side walls being formed with recesses extending inwardly from the vertical corners of the container, laterally extending tabs on each end of the upwardly extending flaps on the closure 55 panel, said tabs being adapted to fit flatwise into said recesses to lie substantially flat against the outer panels of said double thickness side walls and contacting edgewise against the recessed edges of the inner wall panels, whereby 60 said closure is held in place within the container.

BRADFORD W. BROWN.
